(57) **CLAIM**

The ornamental design for a livewell drain, as shown and described.

DESCRIPTION

FIG. 1 is a perspective view of a livewell drain in an open position.

FIG. 2 is a top view of the livewell drain of FIG. 1.

FIG. 3 is a bottom view of the livewell drain of FIG. 1.

FIG. 4 is a front view of the livewell drain of FIG. 1.

FIG. 5 is a back view of the livewell drain of FIG. 1.

FIG. 6 is a left side view of the livewell drain of FIG. 1.

FIG. 7 is a right side view of the livewell drain of FIG. 1.

FIG. 8 is a perspective view of the livewell drain in a closed position.

FIG. 9 is a top view of the livewell drain of FIG. 8.

FIG. 10 is a bottom view of the livewell drain of FIG. 8.

FIG. 11 is a front view of the livewell drain of FIG. 8.

FIG. 12 is a back view of the livewell drain of FIG. 8.

FIG. 13 is a left side view of the livewell drain of FIG. 8; and,

FIG. 14 is a right side view of the livewell drain of FIG. 8.

The broken lines depict portions of the livewell drain and

environmental subject matter that form no part of the

claimed design.
